(57) **CLAIM**

The ornamental design of a powered vehicle, as shown and described.

DESCRIPTION

FIG. 1 is a front and top perspective view of the design of a powered vehicle of the present invention. The seat portion mounted on the rear seat post, as illustrated in this FIG. 1 and in subsequent figures, is shown in phantom, is hereby disclaimed and does not form a part of the present design. FIG. 2 is a rear and top perspective view of the powered vehicle shown in FIG. 1.

FIG. 3 is a front elevational view of the powered vehicle shown in FIGS. 1 and 2.

FIG. 4 is a rear elevational view of the powered vehicle shown in FIGS. 1-3.

FIG. 5 is a right side elevational view of the design of the powered vehicle shown in FIGS. 1-4.

FIG. 6 is a left side elevational view of the powered vehicle shown in FIGS. 1-5.

FIG. 7 is a top plan view of the powered vehicle shown in FIGS. 1-6.

FIG. 8 is a bottom plan view of the powered vehicle as shown in FIGS. 1-7.

FIG. 9 is a front and top perspective view of the design of a powered vehicle of the present invention, similar to that shown in FIG. 1 but with the phantom seat portion removed; and,

FIG. 10 is a top plan view of the powered vehicle of the present invention, similar to that shown in FIG. 7 but with the phantom seat portion removed.
